[57] CLAIM

The ornamental design for a motorcycle utility box, as
shown and described.

DESCRIPTION

FIG. 1 is a perspective view of the motorcycle utility
box showing my new design, the broken lines being for
illustrative purposes only;

FIG. 2 is a side elevational view thereof, the other side
being substantially a mirror image of the side shown
herein;

FIG. 3 is a rear elevational view thereof;

FIG. 4 is a top plan view thereof;

FIG. 5 is a front elevational view thereof;

FIG. 6 is a bottom plan view thereof; and

FIG. 7 is a perspective view of the motorcycle utility
box showing a second embodiment of my new design,
the differences being in the addition of a top rack, tail
light, side directional turn lights, side reflectors and
snap-on coverings for the forward side pouches.

FIG. 1.**FIG. 2.****FIG. 3.****FIG. 4.****FIG. 5.****FIG. 6.****FIG. 7.**
